UNITED STATES PATENT OFFICE.

JOHN ROSSI, OF JOLIET, ILLINOIS.

REFRIGERATOR.

SPECIFICATION forming part of Letters Patent No. 728,017, dated May 12, 1903.

Application filed January 12, 1903. Serial No. 138,696. (No model.)

To all whom it may concern:

Be it known that I, JOHN ROSSI, a citizen of the United States, residing at Joliet, in the county of Will and State of Illinois, have invented a new and useful Improvement in Refrigerators, of which the following is a specification.

My invention relates particularly to lighting means for refrigerators and other chambers; and my primary object is to provide means whereby the operation of unlatching the door of the chamber serves to close an electric circuit and light a lamp within the chambers.

15 The invention is illustrated in the accompanying drawings, in which—

Figure 1 represents a vertical sectional view of a refrigerator equipped with my improvement, the door of the refrigerator being closed and the light-circuit broken; Fig. 2, a broken sectional view of the same character, but showing the door open and the light-circuit closed; Fig. 3, an enlarged broken view showing a portion of the outside of the refrigerator, and Fig. 4 a horizontal sectional view taken as indicated at line 4 of Fig. 3.

In the preferred construction, A represents a cooling-chamber provided with a door A'; B, a door-securing lever fixed upon the outer end of a bolt a, passing through a portion of the wall of the chamber A adjacent to the free edge of the door; B', a switch having insulated connection with the inner end of the bolt a and operated through the medium of said bolt; B², a keeper for the free end of the hand-lever B, and C an electric light having a circuit C', including the switch B', and supplied from an electric source C².

From the description given it will be understood that in the operation of lifting the hand-lever B to unfasten the door the switch B' is operated to close the lamp-circuit, thereby lighting the lamp, and that the operation of lowering the member B to secure the door breaks the lamp-circuit. It will be understood that any suitable electric source may be employed for energizing the lamp.

Minor changes in details of construction within the spirit of my invention may be made. Hence no undue limitations should be understood from the foregoing detailed description.

What I regard as new, and desire to secure by Letters Patent, is—

The combination of a chamber equipped at its inner side with an electric light and provided with a suitable door, a door-securing lever, a keeper therefor affixed to the outer side of the door, a pivot journaled in the door-frame and having said lever fixedly secured to its outer end, an arm fixed to the inner end of said pivot and bearing a contact-point insulated from said pivot, an electric circuit having a conductor connected with said contact-point, and a fixed contact adjacent to the door-opening in the path of said first-named contact and connected with a conductor of said circuit, substantially as and for the purpose set forth.

JOHN ROSSI.

In presence of—

L. HEISLAR,
ALBERT D. BACCI.
